United States Patent Office

Des. 194,752
Patented Mar. 5, 1963

194,752

TOY FIGURE DEVICE

Bill Markham, Los Angeles, Calif., assignor to Lakeside Industries, Inc., Minneapolis, Minn., a corporation of Delaware

Filed Nov. 8, 1962, Ser. No. 72,437

Term of patent 14 years

(Cl. D34—15)

FIG. 1

FIG. 2

FIG. 1 is a front perspective view of a toy figure device embodying my new design; and

FIG. 2 is a rear perspective view thereof, the end not shown being substantially the same as the end shown but without the protruding handle and the bottom being substantially plain.

I claim:

The ornamental design for a toy figure device, as shown and described.
